J. W. Wetmore,

Washing Machine,

№ 68,921.

Patented Sept. 17, 1867.

United States Patent Office.

J. W. WETMORE, OF ERIE, PENNSYLVANIA.

Letters Patent No. 68,921, dated September 17, 1867; antedated September 7, 1867.

IMPROVED WASHING MACHINE.

The Schedule referred to in these Letters Patent and making part of the same.

TO ALL WHOM IT MAY CONCERN:

Be it known that I, J. W. WETMORE, of Erie, in the county of Erie, and State of Pennsylvania, have invented a new and useful Washing Machine; and I do hereby declare that the following is a full, clear, and exact description of the construction and operation of the same, reference being had to the annexed drawings, making a part of this specification, in which—

Figure 1 is a perspective view.

Figure 2, a vertical longitudinal section through *x y*, figs. 1 and 2, representing a section of the box *E F*, and of the pounder *B B*.

Figure 3, a view of the bottom of the pounder.

Figure 4, a view of the separator; and

Figure 5 a view of a cross-section of the bottom of the pounder through *i*, fig. 2, or *z z*, fig. 3.

Fig. 1. *A*, the wash-box, about four feet long, twenty inches wide, and eighteen inches deep, with slanting sides, and perpendicular ends. *B*, the rocking pounder. *C*, handle, frame, or lever, by which the pounder is moved back and forth. *f g h i*, weight-box. *t* and *u*, staples to which hooks are attached, such as *w x*, fig. 2.

Fig. 2. *a b*, curved base-pieces of the pounder. *c c*, slats fastened to the base-pieces. These are represented by *i j*, fig. 3. *d d*, India-rubber pieces nailed to these slats. They are seen in full at *k l*, fig. 3. *i' i' i''*, movable slats with notched ends, fully shown in fig. 5, and at *m n*, &c., fig. 3. They are held in place as represented, and slide readily in the grooves. *n*, a fixed slat, fastened to the base-pieces. *g h*, fig. 3, is the view of it from the under side of the pounder. *j j*, pins of the separator. *l m*, separator, used to keep the sliding-slats apart when the pounder is used only for pressing the clothes, which are placed on the bottom of the box *G K*. *p r*, one of two wire springs inside of the posts, the upper ends fastened to the braces at *r*, and the lower ends to the movable slat *n*. The places of fastening the lower ends are *q* and *q'*, fig. 3. When the separator is removed, and the hook, which is on *v*, is released from the catch on *n*, the springs draw all the movable slats together back towards *e f*, fig. 3. *E F*, section of the wash-box. *G K*, section of the slat-bottom of the wash-box. *w x*, hook to hold the pounder up while the clothes are arranged. *y*, wedge to hold the separator. *z h*, hinged staples to hold the end of the separator.

Fig. 3. The movable slats are represented as drawn back, leaving a space between the slats *g h* and *q q'*. *r r*, notches in the slats, in which to take hold of the slat *q q'*, to draw it back to be hooked by *w*. *s*, place of the catch of the hook *w*, on the opposite side. *w*, hook to hold *q q'* back and take the pressure off of the movable slats. *x y*, line of the section through the bottom, represented by fig. 2. The base-pieces, springs, standard-braces of fig. 2, are then represented, as viewed from the inside of the pounder.

Fig. 4. *a b*, separator. *e*, wedge of the separator. *d d*, wedge-shaped pins that fall between the movable slats. *f f*, two of the movable slats. *g* and *h i*, staples to hold the separator in place.

The machine is operated as follows, (the references to the drawings being to fig. 2 unless otherwise specified:) The pounder is locked back, as represented. The separator *l b* is removed, and the slat *n* drawn back and fastened by the hook *w*, fig. 3. The movable slats are all then slipped back together, and rest against *n*. The lighter articles to be washed are then drawn half through between the flexible slips *d*, and the slats *e*, their ends hanging down. One of the heavier articles, which is unequally soiled, is placed above the movable slats, and the soiled parts, such as wristbands and neckbands, are thrust through the openings, and held by the slat *i* pressed against them. Another of the heavier articles is placed above these slats, and the parts to be washed placed below through the space *k'* and slat *i'* pressed against them, and so on until all the articles are placed or the spaces occupied. The slat *n* is released from the hook and is drawn back by the springs, thereby pressing all the movable slats together. Hook *w x* is then detached at *x*, and the pounder *B* is rocked by the lever or handle *R* on the bottom *G K*. The proper pressure is then obtained by varying the weights in the box *g f' f''*. While these articles are thus held by the slats, others may be placed on the bottom, and the pounder rocked over them. With the separator in place, the pounder may be thus used without any articles held by the slats.

The principle of my invention is, the holding of the articles to be washed on the under side of the rocking pounder, and alternately pressing them on to the bottom of the wash-box and lifting them from it.

Other modes of applying the principle are as follows: Instead of the springs *p r*, fig. 2, there can be strips of India rubber nailed on or near the ends of the movable slats, connecting them together and to the fixed slat *f e*, fig. 3. This would do away with the necessity of using the separator. The pounder may be constructed with all movable slats or with them all fixed. The handle *C*, fig. 1, may be a single bar, attached at *l*. The pounder may also be rocked by a rope reaching from *l* to *v* and *d*, fig. 1. Openings may be cut in the movable slats, as marked at *o p*, fig. 3, and the pounder then used without putting in the separator.

What I claim as my invention, and desire to secure by Letters Patent, is—

1. The slats *i j*, faced with flexible strips *k l*, and the movable slats *m n*, fig. 3, constructed and operated as described.
2. The combination in the pounder *B* of the slats, faced with strips *k l*, movable slats *m n*, hook *w*, fig. 3, weight-box *g' f''*, lever *R*, and springs *p r*, fig. 2, arranged as and for the purposes set forth.
3. The combination of the separator *l m*, fig. 2, with the pounder *B*, as and for the purposes described.

J. W. WETMORE.
